US0D1085863S

(12) **United States Design Patent** (10) **Patent No.:** **US D1,085,863 S**
(45) **Date of Patent:** ** *Jul. 29, 2025

(54) **PACKAGE**

(71) Applicant: **SPIGEN KOREA CO., LTD.**, Seoul (KR)

(72) Inventors: **Hyunjun Yang**, Seoul (KR); **Yunhwan Kim**, Seoul (KR); **Deokhun Moon**, Seoul (KR); **Goeun Lee**, Seoul (KR)

(73) Assignee: **SPIGEN KOREA CO., LTD.**, Seoul (KR)

(*) Notice: This patent is subject to a terminal disclaimer.

(**) Term: **15 Years**

(21) Appl. No.: **29/652,373**

(22) Filed: **Jul. 28, 2020**

(51) LOC (15) Cl. **09-03**

(52) U.S. Cl. **D9/415**
USPC ....

(58) **Field of Classification Search**

(57) **CLAIM**

The ornamental design for a package as shown and described.

DESCRIPTION

FIG. 1 is a front perspective view of the package showing our new design according to a first embodiment of our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front elevational view of the package showing our new design according to a second embodiment of our design.

The broken lines throughout the drawing figures depict portions of the package that form no part of the claimed design. The broken lines and regions bounded by broken lines form no part of the claimed design.

1 Claim, 8 Drawing Sheets
